DRESS

Joseph T. Cukor, Tuckahoe, N. Y.

Application August 17, 1935, Serial No. 36,728

2 Claims. (Cl. 2—74)

This invention relates to wearing apparel, and particularly to an improved dress, the object being to provide a construction which may present a dress of conventional design while at the same time providing means for expansion from time to time.

Another object of the invention is to provide a dress which in appearance presents the usual style of the day, but which has formations capable of being released so that the dress may be utilized as a maternity dress.

A further object, more specifically, is to provide a dress which may be let out from time to time by pregnant women, but which in its various stages of adjustment will present a dress of the conventional prevailing styles and one which will not be appreciably distorted by the enlarging condition of the wearer.

In the accompanying drawings:

Fig. 1 is a front view of a dress disclosing an embodiment of the invention, the same illustrating a dress before any of the parts have been released or adjusted;

Fig. 2 is a rear view of the structure shown in Fig. 1;

Fig. 3 is a fragmentary view on an enlarged scale of the central part of the dress as illustrated in Fig. 1, certain parts being broken away for illustrating the arrangement of a supporting and confining belt embodying certain features of the invention;

Fig. 4 is a sectional view through Fig. 3 approximately on line 4—4;

Fig. 5 is a sectional view through Fig. 4 approximately on the line 5—5; and

Fig. 6 is a plan view on a somewhat enlarged scale of the supporting and confining belt shown in Fig. 3.

Referring to the accompanying drawings by numerals, 1 indicates what may be termed the body of the dress which is provided with a skirt section 2 and an upper or waist section 3. The waist section 3 may be provided with long or short sleeves 4 and with a collar 5 or other neck formation as desired. The particular design of dress shown in Fig. 3 forms no part of the present invention but is presented so as to illustrate the invention as it will appear when in use. The skirt 2 and the upper part 3 are preferably made separately and secured together by a line of stitching 6, said line of stitching being at the waistline of the garment. If desired, the skirt 2 and part 3 may be made in one piece, though ordinarily it is made of two pieces and connected together by a seam 6.

At the extreme sides of the garment there are sections 7 and 8 in both the skirt and waist and these sections are left unmolested, but between these sections and the front and rear there are provided a number of pleats indicated by numerals 9, 10, 11, 12, 13, 14, 15, and 16. From Fig. 4 it will be observed that at the front near each side there are two pleats extending vertically above and below the waistline. At the rear there are also provided two pleats near the sides of the garment extending above and below the waistline. The widest portion of these pleats is at the waistline and from this point they taper to a point at the top and bottom, as illustrated particularly in Fig. 5. When a woman is using the garment and becomes somewhat enlarged, one or more of these pleats is let out by cutting the thread holding the same. Usually one pleat on each side of the front is let out first and then one pleat on each side of the rear is let out second. This continues as the woman enlarges until all the pleats have been let out, if necessary.

As is well-known, a pregnant woman becomes enlarged above the waistline as well as below the waistline at the front and many times at the rear, so that the pleats extend both above and below the waistline, and any of these pleats may be removed at any time to take care of the enlargement either at the front or rear, above or below the waistline. The removal of the pleats will not materially change the general appearance of the dress as they are usually removed in pairs whereby an even balance or uniform appearance is maintained in the dress.

During the later stages of pregnancy there is quite often an appreciable enlargement at the front which in an ordinary dress would raise the front of the dress undesirably. Sometimes the dress at the rear is also raised undesirably. To take care of these conditions, there is provided circumferentially extending tucks 17 and 18 at the front which are really double-ended pleats as they taper or merge into a point adjacent the respective darts 9 and 16 at the front. If the enlargement is only below the waistline the pleat 17 will be eliminated by cutting the threads holding the same, but if the bust should become enlarged the pleat 18 in the upper part of the body is eliminated. This will give additional material at the front of the dress which will result in maintaining the length of the dress normal, and the bottom of the dress always in a horizontal plane when in use. The same action may take place in the rear though usually to a lesser extent. For instance, as shown in Fig. 2, there is only one

double-ended pleat 19 though more could be provided if desired. In Fig. 1 there is only one upper and one lower pleat though more could be utilized if necessary or desirable.

5 By providing a dress of a desired style and then forming the various pleats as specified, namely the vertical darts at the front and rear and the horizontal darts at the front and rear, a desired appearing dress is presented which may be worn 10 at any time and which will not give the appearance of a maternity dress but will give the appearance of an ordinary dress as is commonly worn. As the dress is let out and enlarged above and below the waistline the same style and general 15 appearance of the dress is maintained and the horizontal level of the bottom of the dress is also maintained. In this way a woman wearing the dress may present a proper and pleasing appearance for almost the entire period of pregnancy. After this period is over, if it should be desired to further utilize the dress for ordinary wear, the various pleats may be re-formed and stitched in place so that the original appearance of the dress will be presented and may be worn 20 25 as a conventional dress without any suggestion or intimation that it is of a special type.

In order to take care of certain conditions and to augment the formation shown in Figs. 1 to 5, there is provided a supporting belt structure 20 30 as illustrated in Figs. 3 and 6. This belt structure is preferably tacked to the dress body 1 so as to be positioned substantially as shown in Fig. 3, and thereby provide a proper support and slight constricting action at the point of greatest enlargement. The belt 20 may be made of any suitable textile fabric in a similar way to the dress, but is preferably made from some strong fabric so as to provide a supporting belt that will take some of the strain off of the dress proper. 35 40 The belt 20 is made in two parts stitched together at 21 with an enlarged portion 22 adapted to fit across the front of the person using the device. The enlarged portion 22 merges into bands 23 and

24 which are sufficiently long to extend around the body. A buckle or other securing means may be used to connect the free ends of the bands 23 and 24 together. If preferred, snap fasteners or even a safety pin may be used instead of a buckle. 5 Some form of adjustable, disengageable, fastening means is desirable as it is necessary to let out the effective length of the belt from time to time.

In addition to these fastening means just described, there are provided a number of tucks 25, 10 said tucks being equal in number to the pleats shown in Fig. 4 and placed substantially opposite these pleats so that whenever a pleat is let out one of the tucks 25 is let out. Preferably the belt 22 is merely tacked to the lower edge portion of 15 the upper part or waist section 3 of the dress, but if desired the front part could be permanently connected thereto.

I claim:

1. A dress comprising a body formed with upper 20 and lower parts, said upper and lower parts having groups of longitudinally extending pleats at the front and rear near the sides extending from the waistline of the dress, said pleats being capable of being opened at any time, and circumferentially 25 extending tucks at the front and rear, said tucks extending from one group of pleats to the other of the body adjacent the waistline for varying the effective length of the garment at the front and rear. 30

2. A maternity dress comprising a body structure having above and below the waistline pleated formations adjacent the sides at the front and back, said pleated formations extending longitudinally of the dress, and a series of tucked formations arranged at the front and back of the dress extending circumferentially, certain of said tucked formations being above and certain below the waistline, all of said tucked formations being capable of being independently eliminated for 40 enlarging the garment circumferentially and also longitudinally. 35
